VACUUM TUBE CONSTRUCTION

Charles J. Kayko, Jackson, Mich., assignor, by
mesne assignments, to The Sparks-Witting-
ton Company, Jackson, Mich., a corporation of
Ohio

Application August 12, 1929, Serial No. 385,173

6 Claims. (Cl. 250—27.5)

My invention relates to vacuum tubes of the type employing cathode, grid and plate elements.

An object of my invention is to devise simple and rugged structure for supporting and maintaining the elements of a vacuum tube in proper spaced relation.

Another object is a novel method of mounting and centering the filament within the grid element.

10 A further object is to simplify the method of assembly of the elements of the novel vacuum tube structure which I have devised.

My invention is illustrated in the accompanying drawings in which:

15 Figure 1 is a side elevational view of the vacuum tube assembly mounted upon the stem of the tube;

Figure 2 is a side view of Figure 1 with a part of the plate element broken away;

20 Figure 3 is a plan view of the assembled structure shown at Figures 1 and 2;

Figure 4 is a unit assembly of the supporting wires and the filament mounted upon the stem of the tube;

25 Figure 5 is a side view of a unit assembly of the plate and grid elements;

Figure 6 is a side view of Figure 5; and

Figure 7 is a plan view of the unit assembly shown in Figures 5 and 6.

30 Referring to Figures 1, 2 and 3, I have shown the assembled structure of the vacuum tube which I have devised mounted upon the stem 1, ready to be sealed into the glass envelope (not shown). 1a indicates the usual sealing-off tube connection to

35 the stem 1. The plate element 2 comprises two like sheet-metal elements 2a and 2b welded together at spaced points along the lines indicated at 2c and 2d. The edges of the plate members beyond the welding lines are formed to encircle and

40 clamp the supporting wire rods 2e and 2f, the lower ends of which are welded, respectively, to supporting wire angle-rods 2g and 2h sealed into the pinch of the stem 1. The angle-rod 2g is provided with a terminal wire 2i, which serves as

45 the leading-in wire for the plate element 2. The grid comprises a wire 3 wound in helical fashion around two parallel wire rods 3a and 3b, each turn of the wire 3 being preferably secured to the rods as by welding. The rods 3a and 3b are welded at

50 their lower ends to angle-rods 3c and 3d sealed into the stem 1. Angle-rod 3d is provided with a terminal wire 3e, which serves as a leading-in wire for the grid 3. The cathode comprises a

55 nickel filament wire 4, the two ends of which are welded to wire angle-rods 4a and 4b sealed into

the pinch of stem 1. The middle of the filament 4 is looped back to a point between the two ends and is anchored by a wire hook 4c welded to an angle-rod 4d sealed into the pinch of stem 1. Angle-rods 4a and 4b are provided with terminal wires 4g and 4h which serve as leading-in conductors for the filament. The upper loops of filament wire 4 are supported by spring-wire hooks 4e and 4f supported from rods 5f and 5g anchored in a glass arbor 5. The filament 4 may be treated 10 or coated in any well known manner to increase its electron emitting capacity.

The arbor 5 is supported from the plate element 2 by two inverted U-shaped wire rods 5a and 5b, one leg of each being welded to the plate 2, and the free ends being embedded in the arbor at points near the ends. The arbor 5 is also partially supported from angle-rod 4d by means of rod 6 welded to the end of angle-rod 4d and to a rod 5c anchored in arbor 5. The grid structure is 20 secured against lateral displacement by two angle-rods 5d and 5e, one end of each being anchored in arbor 5 and the other ends being welded respectively to the supporting rods 3a and 3b.

The rod 6 extends below the angle-rod 4d and supports at its lower end a flashing cup 7, which contains suitable flashing material such as magnesium.

In the manufacture of my tube, I prefer to assemble the structure in unit assemblies as indicated in Figures 4 to 7. The stem assembly indicated in Figure 4 is preferably formed by sealing into the pinch of the stem 1 seven wires of equal length corresponding to the wire rods 2g, 3c, 4a, 4d, 4b, 3d and 2h, respectively. These 30 wires are embedded in the pinch in one operation, and are then cut to proper length and formed to the proper shape. Wire 4d is bent at right angles to the plane of the pinch, and the remaining wires are bent in the plane of the 35 pinch and symmetrically about a central axis.

The filament 4, with wire hook 4c, is next placed in position and the ends welded to supporting wires 4a and 4b, the hook being welded to wire 4d.

The arbor assembly is also preferably formed 45 by embedding seven straight wires into the glass rod 5 in one operation. The wires are then cut to the proper length and formed to the proper shape. The arbor assembly is then secured to the plate element assembly by welding wire rods 5a and 5b to the plate element along the lines 2c and 2d.

The grid assembly comprising the wire grid 3 wound around parallel wire rods 3a and 3b is next centered within the plate element 2, and

50 the wires 3a and 3b are welded to the angle-rods 3c and 3d.

55 The cathode 4 is then centered within the grid 3, and the wires 4a and 4b are welded to the angle-rods 4c and 4d.

60 The filament 4 is then centered within the cathode 4, and the wires 2e and 2f are welded to the angle-rods 2c and 2d.

65 The plate element 2 is then centered within the grid 3, and the wires 5a and 5b are welded to the angle-rods 5c and 5d.

70 The arbor 5 is then centered within the plate element 2, and the wires 6 and 7 are welded to the angle-rods 6c and 6d.

75 The assembly is then sealed into the glass envelope.

80 The filament 4 is then heated to incandescence, and the glass envelope is evacuated.

angle-rod 5d and 5e are welded to the vertical rods 3b and 3a respectively. The stem assembly shown in Figure 4 is now inserted in the grid and plate assembly shown in Figures 5 to 7, and the 5 plate supporting rods 2e and 2f are welded to the angle-rod 2g and 2h, respectively, and the lower ends of the grid supporting rods 3a and 3b are welded, respectively, to angle-rod 3c and 3d. By this operation the lower end of the grid and 10 plate elements are automatically positioned with respect to each other by the angle-rod supported in the pinch of stem 1. The vertical rod 6 is next welded to the wire 5c mounted in arbor 5 and to the end of angle-rod 4d embedded in the pinch 15 of stem 1 and extending at right angles to the plate and grid elements. This arrangement supplies added strength against lateral displacement or bending of the grid and plate elements in a plane at right angles to the plane of the pinch 20 of the stem, and also serves to help support the arbor 5 with its assembly. The spring hooks 4e and 4f are next hooked to the upper loops of filament 4 and are welded, respectively, to rods 5f and 5g supported from arbor 5. Supporting rods 25 5f and 5g are made of ductile wire such as copper or nickel, and will remain in any position to which they are bent unless acted upon by a force greater than the resistance to bending. As shown in Figure 1, the spring hooks are welded to rods 5f and 5g in such position that the filament loops are 30 off-center with respect to the grid element. After the spring hooks are welded to the supporting rods these ductile rods are bent to the dotted position shown in Figure 1 to place the springs under 35 proper tension and to center the loops of filament 4 with respect to the grid element. The filament is shown properly centered in Figure 3.

It will be understood that the assembled structure shown in Figures 1 to 3 is sealed within a 40 glass envelope which is then exhausted and sealed-off through tube 1a, and a connector plug is mounted on the envelope in the usual way.

From the foregoing description of my invention, it will be apparent that the rugged structure which I have devised is particularly effective in reducing microphonic and other noises due to mechanical vibration of the tube elements.

What I claim is:

1. In a vacuum tube structure, the combination 50 of a stem having a single pinch, a plate element supported from said pinch by two conductors embedded in said pinch at spaced points, an insulating arbor supported from said plate element intermediate the ends thereof, a third conductor embedded in said pinch and extending at right angles to the plane of the plate supporting conductors, a connection between said third conductor and said insulating arbor, whereby said plate element is given lateral support, a grid element 55 located within said plate element and having supporting rods extending beyond the end of the plate element, and angle-rod embedded in said arbor and extending across the end of said plate element and being secured to said grid rods in crossed engagement.

2. In a vacuum tube structure, the combination 60 of a plate element including two spaced parallel conducting walls, a grid element mounted between said walls comprising two spaced parallel rods extending beyond said walls at one end, and having a wire wound around said rods in spaced convolutions, and an insulating arbor supported from one of said walls intermediate the ends thereof by a pair of U-shaped brackets and from 65 said parallel grid rods by means of a pair of angle rods anchored in said arbor and extending parallel to the plate beyond the end thereof, and then across the end of the plate to the grid rods at right angles thereto, a looped filament located within said grid element having at least one bight, a ductile rod imbedded in said arbor and extending beyond the end of said plate element, and a spring member supported by said ductile rod and having its free end engaging the bight of said filament, said ductile rod being bent in a direction

of angle rods anchored in said arbor and extending parallel to the plate beyond the end thereof and then across the end of the plate to the grid rods at right angles thereto.

3. In a vacuum tube structure, the combination 70 of a stem having a single pinch, a plate element supported from said pinch by two conductors imbedded in said pinch at spaced points, an insulating arbor supported from said plate element intermediate the ends thereof, a third conductor imbedded in said pinch and extending at right angles to the plane of the plate supporting conductors, a connection between said third conductor and said insulating arbor whereby said plate element is given lateral support, a grid 75 element located within said plate element and having supporting rods extending beyond the end of the plate element, angle rods imbedded in said arbor and extending across the end of said plate element and being secured to said grid rods in crossed engagement, a looped filament located within said grid element having at least one bight, and having its terminals secured to lead-in conductors in said pinch centered with respect to said grid element, a ductile rod imbedded in 80 said arbor and extending beyond the end of said plate element, and a spring member supported by said ductile rod and having its free end engaging the bight of said filament, said ductile rod being bent in a direction away from the plane of the plate element to tension said spring member and said filament, and to center a loop of said filament with respect to said grid element.

4. In a vacuum tube structure, the combination 85 of a stem having a single pinch, a plate element supported from said pinch by two conductors imbedded in said pinch at spaced points, an insulating arbor supported from said plate element intermediate the ends thereof, a third conductor imbedded in said pinch and extending at right angles to the plane of the plate supporting conductors, a connection between said third conductor and said insulating arbor whereby said plate element is given lateral support, a looped filament located within said plate element having at least one bight, a ductile rod imbedded in said arbor and extending beyond the end of said plate element, and a spring member supported by 90 said ductile rod and having its free end engaging the bight of said filament, said ductile rod being bent in a direction away from the plane of the plate element to tension said spring member and said filament, and to center a loop of said filament with respect to said plate element.

5. In a vacuum tube structure, the combination 95 of a plate element including two spaced parallel conducting walls, a grid element mounted between said walls comprising two spaced parallel rods extending beyond said walls at one end, and having a wire wound around said rods in spaced convolutions, and an insulating arbor supported from one of said walls intermediate the ends thereof by a pair of U-shaped brackets and from said parallel grid rods by means of a pair of angle rods anchored in said arbor and extending parallel to the plate beyond the end thereof, and then across the end of the plate to the grid rods at right angles thereto, a looped filament located within said grid element having at least one bight, a ductile rod imbedded in said arbor and extending beyond the end of said plate element, and a spring member supported by said ductile rod and having its free end engaging the bight of said filament, said ductile rod being bent in a direction

away from the plane of the plate element to tension said spring member and said filament and to center a loop of said filament with respect to said grid element.

5. In a vacuum tube structure, the combination of a plate element including two spaced parallel conducting walls, an insulating arbor supported from one of said walls intermediate the ends thereof by a pair of U-shaped brackets, a

10 looped filament located between said walls having

at least one bight, a ductile rod imbedded in said arbor and extending beyond the end of said plate element, and a spring member supported by said ductile rod and having its free end engaging the bight of said filament, said ductile rod being bent in a direction away from said walls to tension the spring member and said filament and to center a loop of said filament with respect to said plate element.

CHARLES J. KAYKO. 10
